UNITED STATES PATENT OFFICE

2,176,805

BRICK

Josef Scheibl, Wels, Austria, assignor to Juliana
Orbell, Brooklyn, N. Y.

Application May 13, 1937, Serial No. 142,338

7 Claims. (Cl. 72—41)

This invention refers to building material, and more especially to a hollow brick construction having surface grooves and interlocking elements on the side and end surfaces.

5 An object of the invention is to provide a brick with an interrupted joint or union for fastening two adjacent bricks.

Another object is to provide a brick with a horizontal interlocking groove.

10 A further object is to provide a brick with horizontal grooves or channels for resisting or eliminating the penetration of moisture.

15 A further object is to provide a brick with horizontal ridges for resisting the penetration of moisture.

Finally, an object is to provide a brick with a hollow section for the purpose of lessening the weight of the brick for the same strength and also for insulating purposes, to prevent the 20 transmission of heat and cold.

All these and other objects are attained by the method and means now to be described, and illustrated in the accompanying drawing, in which—

25 Figure 1 is a perspective view of a preferred embodiment of the brick comprising this invention.

Fig. 2 is a top plan view of the brick of Fig. 1. Fig. 3 is a side elevational view of the brick 30 of Fig. 1, and

Fig. 4 is a view similar to that of Fig. 2 but showing two bricks with the mortar joints therebetween.

Like numerals refer to like parts throughout the several views.

The brick is, of course, generally rectangular in shape. Its side surfaces 10—10 have horizontally disposed parallel grooves 11, moulded or otherwise formed in the surfaces during the 35 process of manufacture. There are also similar parallel grooves 12—12 in the upper and lower surfaces as shown. The upper surface also contains two parallel longitudinally disposed projections or ribs 13—13 centrally positioned as shown; and the lower surface contains a somewhat corresponding grooved section 14 as wide as the ribs between and including ribs 13 and of a depth equal to or slightly more than the height of said ribs 13. This provides an interlock between the upper and lower surfaces of adjoining bricks 40 when in operative position in the wall.

The ends of the bricks which are opposite one another have a generally flat vertical surface except for two spaced vertically disposed V-shaped notches or grooves 15—15 into which

mortar 16, Fig. 4, is placed when building the walls of said bricks, for the purpose of retaining them end to end in the wall.

Two centrally disposed horizontal openings 17—17 extend completely through the brick from 5 one end to the other, as shown in Fig. 1, and on each side of them are four parallel vertically disposed openings 18—18 also extending through the brick from one end to the other. It will be noted that the adjacent side openings 18—18 are 10 of different heights with the intermediate horizontal walls staggered as shown, so that a short and a long opening are positioned together horizontally to form the staggered separating wall as clearly shown in Fig. 1.

15 Thus, it will be seen that this invention provides an improvement in hollow brick having horizontal grooves on horizontal surfaces forming channels in the seams between adjoining brick.

20 The bricks are laid into the wall by pouring the mortar 16 from the top to fill the two spaced openings between the brick ends formed by the notches 15—15 as shown in Fig. 4. This does away with the tiresome application of mortar by hand.

The openings 17, 18 are air channels to improve the thermal insulation of the brick as well as to lighten its weight.

25 Of course it will be understood that the number and shape of the various grooves and ribs as well as air openings may vary according to desire.

The outer grooves 11—11, which may be applied to but one side surface as shown, serve to 35 hold the mortar or stucco coating which is applied to the surface of the wall after completion. It serves to retain the stucco permanently as part of the wall surface.

It should be noted also that any moisture 40 which enters from the outside of the wall must pass the vertical grooves 12—12 and bridge over the ribs 13—13 and again pass the grooves 12—12 along the inner side of the brick before the moisture can penetrate through to the inside. This has been found from experience to provide an effective moisture seal.

45 It will be further noted that the grooves 15—15 positioned vertically in the ends of the brick are separated by a wall surface from entering the 50 central openings 17—17. This means that when adjacent bricks are positioned together and mortar applied to these openings 15—15 that no portion of it will flow into the central openings 17—17 so there will be a continuous aligned 55

opening or pair of openings from one end of the wall to the other. By thus placing a plurality of the bricks in end to end, substantial meeting engagement and then pouring mortar into the spaced channels formed by the vertical walls of the adjacent grooves or recesses in the adjoining bricks, two substantially separate mortar joints are formed in each pair of adjoining bricks which aid considerably in preventing moisture from passing through the wall so formed. Furthermore, since, as will be apparent from both Figs. 2 and 4, the central end wall portions 20 and the outer end wall portions 21 are on the same plane, the portions 21 will be in substantially meeting engagement when the bricks are placed end to end, and accordingly little or none of the mortar will pass to the exterior of the wall so formed. Accordingly, one of the surfaces may be used for an attractive outer wall with little or no mortar showing. Moreover, only a small amount of mortar will enter the openings 18-18, sufficient only to aid in binding the bricks together. These interrupted air spaces, therefore, will also serve additionally for thermal insulation. Note, then, that the mortar joint between the adjacent bricks is interrupted by the hollow spaces 17-17 so that in case of a driving rain the mortar prevents the moisture from seeping through.

Bricks of this character have many advantages over ordinary brick. For instance, these hollow bricks are laid piece by piece and the intervals filled with thin flowing mortar, thus affecting a considerable labor saving. The brick reduces transportation costs due to its large saving in weight to and on the building site. This saving amounts to from 30 to 40%. The brick also saves in the amount of mortar used through its joint construction, there being practically no loss in mortar possible. Tests show that actually only half the mortar is used as with ordinary brick. Also the strength or reliability of the wall is not dependent upon the carefulness of the brick layer, since the stability of the work especially at the joints is secured through the structure of said joints. Also the brick is an ideal plaster carrier, mortar folds forming on the outer grooves during the placing of the plastering mortar which prevents the dropping off of the plaster or stucco, which condition happens frequently with large surfaces made from ordinary brick. Moreover, this type of brick may be laid in the same way as the ordinary brick and the joints filled out, no auxiliary implements being necessary. Furthermore, to obtain the same insulating effect of an ordinary brick wall of a certain thickness requires a wall only two-thirds as thick when formed with the hollow brick of this invention. The interruption of the mortar joints prevents the driving rain and moisture from penetrating and yet is accomplished with a comparatively large-sized hollow brick, something not heretofore accomplished. Finally, with this type of brick quick drying out of the wall is effected due to the small amount of mortar used and the rapid progress in construction. Any new building erected with these bricks, it has been found, is ready to be dry-plastered within a few days without using special insulation means, making possible thereby an early occupation of the structure and thus a quicker amortization of the invested capital.

Having now described the invention, what is claimed as new and for which Letters Patent of the United States is desired, is:

1. A building brick having a centrally disposed horizontal opening throughout its length, a plurality of parallel side openings on each side of said horizontal opening, and spaced vertically-disposed notches in its end walls, into which mortar is adapted to be poured to form a joint between adjacent brick ends in a wall, said notches connecting with said side openings only.

2. The invention as in claim 1, including longitudinal spaced grooves on the upper and lower surfaces of the brick and terminating in said notches.

3. A building brick adapted to be formed on a brick-making machine, and having a centrally-disposed horizontal opening throughout its length, a plurality of parallel side openings on each side of said horizontal opening, spaced vertically-disposed outwardly-beveled notches in its end walls into which mortar is adapted to be poured to form a joint between adjacent brick ends in a wall, said notches connecting with said side openings only, said horizontal opening and side openings extending continuously through the brick from end to end.

4. The invention as in claim 3, including a projection above and corresponding groove below said horizontal opening and between said side openings.

5. A building brick comprising upper and lower wall members and spaced side wall sections, each side wall section comprising a plurality of spaced, vertical walls, the upper and lower wall members connecting the spaced vertical walls comprising each wall section, such upper and lower wall members also connecting the spaced side wall sections, the terminals of each side wall section having a vertical recess therein extending from the upper to the lower wall members, whereby when such bricks are laid in end to end engagement a mortar groove will be formed by each adjacent pair of recesses.

6. A building brick comprising upper and lower wall members and spaced side wall sections, each side wall section comprising a plurality of spaced, vertical walls, the upper and lower wall members connecting the spaced vertical walls comprising each wall section, such upper and lower wall members also connecting the spaced side wall sections, the side wall section being spaced apart a greater distance than the vertical walls comprising each section, a plurality of spaced, longitudinal ribs on the exterior surface of one of the wall members, the other wall member having a longitudinal recess therein adapted to receive the ribs of the adjacent brick therein when the bricks are formed into a wall.

7. A building brick comprising upper and lower wall members and spaced side wall sections, each side wall section comprising a plurality of spaced, vertical walls, the upper and lower wall members connecting the spaced vertical walls comprising each wall section, such upper and lower wall members also connecting the spaced side wall sections, a plurality of spaced longitudinal ribs formed on the upper wall, the lower wall having a longitudinal recess of such width as to receive such ribs formed on the brick immediately there-beneath, each end wall of the brick having a plurality of spaced vertical recesses therein adapted to form vertical mortar grooves when the bricks are laid in end to end engagement.
